UNITED STATES PATENT OFFICE.

THERON B. LAMBERT AND JAY McCOMBS, OF MURRAY, KENTUCKY.

APPARATUS FOR PRESSING TROUSERS WHILE ON WEARER.

Application filed November 6, 1925. Serial No. 67,396.

Our present invention pertains to trousers pressing apparatus, and has for one of its objects the provision of an apparatus through the medium of which the legs of trousers on a wearer may be expeditiously and adequately pressed so as to provide the trousers legs with dressy creases at the front portion and back portion thereof.

Another object of the invention is the provision of an apparatus for the purpose indicated, having means for fastening a trousers leg in accurate position relative to the apparatus precedent to the pressing of the leg so as to assure the production of a crease in the leg at the proper point and in a finished manner.

Another object of the invention is the provision of an apparatus for the purpose ascribed, susceptible of being operated with but little effort.

Another object is the provision of an apparatus for the purpose indicated in which the irons are maintained in a heated state by peculiar and advantageous electric means.

To the attainment of the foregoing, the invention consists in the improvement as hereinafter described and definitely claimed.

In the accompanying drawings, forming part of this specification:—

Figure 1 is a side elevation of the apparatus constituting the best practical embodiment of our invention of which we are cognizant.

Figure 2 is an enlarged fragmentary horizontal section taken in the plane indicated by the line 2—2 of Figure 1, and showing the irons and the arrangement of the electric heating elements relative thereto.

Figure 3 is an enlarged horizontal section with parts broken away, the section being taken in the plane indicated by the line 3—3 of Figure 1, looking upwardly.

Figures 4 and 5 are detail elevations of the irons shown in Figure 1, the said views of Figures 4 and 5 being at right angles to each other.

Figure 6 is an enlarged plan view of one of the clamps for engaging a trousers leg or portion and contributing to the accurate positioning of the trousers leg or portion relative to the irons of the apparatus.

Figure 7 is a detail view illustrative of one of the electrical heating elements comprised in the improvement.

Similar numerals of reference designate

corresponding parts in all of the views of the drawings.

Among other elements our novel apparatus comprises a base 1, mounted on casters 2, for convenient movement of the apparatus 60 as a unit from one part of a room to another. Appropriately fixed to the central portion of the base 1 and rising therefrom is an upright 3, and fixed in any approved manner on the upper end of the said upright 65 3 is a cap member 4 on the edge of which is an upright bracket 5, the said bracket 5 being, by preference, in substantial parallelism with the upright 3, and being extended above and below the horizontal plane of the cap 70 member 4. The said bracket 5 is connected at 6, preferably in fixed manner, to the edge portion of the cap member 4. On the end portions of the bracket 5 are tubular portions 7 for the reception of the vertical rod 75 8, Figures 2 and 3, and from this it will be understood that the said rod 8 serves to effect connection of the irons of our improvement to the bracket 5 so that the said irons may be conveniently manipulated as occasion demands.

The irons of our improvement are designated by 9 and 10, and may, within the purview of our invention be formed of any material consonant with the purpose of the invention. The said irons have knuckles 11 receiving the rod 8, and each iron has fixed thereto and extending upwardly therefrom an arm 12. The arms 12 serve for the pivotal connection at 13 of clamp members 14, 90 the said clamp members 14 being pivotally connected together at 15, and each being provided at an intermediate point of its length with an apertured and interiorly threaded portion 16, Figure 3. The threads 95 in the portions 16 of the clamp members are reversely directed so that one portion 16 will be adapted to receive and cooperate with the portion 17 of a manipulating rod, and the other portion 16 will be adapted to 100 receive and cooperate with the reversely arranged thread on the other section of the manipulating rod, which other section is numbered 18. The said sections 17 and 18 are connected together by an appropriate universal joint 19, and hence it will be 105 understood that when the hand wheel 20 on the section 17 is turned in one direction the clamp members 14 will be synchronously moved inward, while when the same hand 110

wheel is turned in the opposite direction the clamp members 14 will be moved outwardly. It will also be appreciated from the foregoing that through the medium of the hand 5 wheel 20, the irons 9 and 10 may be moved together and held with their faces in close proximity and under great pressure so as to contribute to the thorough pressing and creasing of the trousers portion interposed 10 between the irons.

Mounted on the rod 8 and disposed in a horizontal plane above the upper end of the irons 9 and 10 is a clamp 30, and similarly mounted on the rod 8 and disposed in a 15 horizontal plane below the lower ends of the irons 9 and 10 is a similar clamp 31. The said clamps are preferably identical in construction, and therefore a detailed description of the clamp illustrated in Figure 20 6 will suffice to impart a definite understanding of both. By reference to Figure 6, it will be understood that both clamps have forward arms on which are rubber grips or jaws 32, and it will also be understood 25 that the members of the clamps are mounted on and swingable about the rod 8, and that one of the rear arms of the members is provided with an apertured lug 33 while the other rear arm has pivoted to it 30 at 34 a curvilinear rack bar 35, the said rack bar 35 being equipped with a handle 36, and being extended through the apertured projection 33 so that the teeth of the rack bar will cooperate with one wall in the said projection 33. The aperture in the projection 33 is sufficiently large to permit of lateral movement of the rack bar 35, and hence said rack bar may be expeditiously and easily fixed to and released from the wall of the 35 aperture in the projection or lug 33. It will also be manifest that the jaws 32 may be quickly affixed in position at opposite sides of a trousers portion so as to securely hold the same, and yet at the proper time, the 40 said jaws 32 may be released for the removal of the trousers portion from between the jaws 32 and also from between the irons 9 and 10.

At the outer side of each iron and appropriately fixed thereto is a casing section 40, and in said casing section 40 is a metallic body 41, between which and the back of the iron is interposed a suitable electric resistance or heating element 42, Figures 2 and 7. It will also be noted by reference to Figure 2 that insulating material 43 is arranged in the casing section 40 and in the relation shown to said section 40 and the metallic body 41, and that dielectric tubular 45 posts 45 extend from the heating element or unit 42 outwardly through the metallic body 41, the insulating material 43 and the casing section 40. As best illustrated in Figure 2, the said tubular posts 44 serve to receive 50 and permit the passage of conductive rods

46, which are in electric connection with the heating elements or units 42, and are designed to be appropriately connected to electric conducting wires 50, Figure 1, which latter may be connected to a plug, not shown, so as to bring about the supply of electric current to our novel apparatus from a conventional outlet box in a building. The said wires 50 may be and preferably are insulated in conventional manner, and are carried through apertures 60 in caps 61 fixed at the outer sides of the casing sections 40. The said caps 61 in the preferred embodiment of our invention are of dielectric material. 70 75 80

In practice, the irons 9 and 10 are separated when not in use, and therefore, it will be understood that when it is desired to use the apparatus, electric current will first be supplied to the heating units 42 in order to adequately raise the temperatures of the irons 9 and 10, and a customer whose trousers are to be pressed steps up into convenient position relative to the irons 9 and 10 and so that the lower clamps 31 may be made to take hold of the cuff at the lower end of one trousers leg. With this done, the operator exerts upward tension on the material in the trousers leg so as to eliminate wrinkles, and the operator then places the upper clamps 30 in engagement with the trousers at the proper point which may be and preferably is above the point where the leg is joined to the body receiving portion of the trousers. Then while the trousers leg is held taut between the clamps 30 and 31, the irons 9 and 10 are brought together at opposite sides of the trousers portion and considerable pressure is imposed against the irons, and the irons are retained under pressure against the trousers portion for a short space of time. In the manner described trousers may be expeditiously and easily pressed while on the wearer, and after the pressing is effected the apparatus may be quickly and easily manipulated for the release of the trousers portion. We would also have it understood here that our novel apparatus is adapted to press and produce creases at the back portions of the legs of trousers as well as at the front portions of said legs. We would also have it understood that in the preferred practice of our invention the material in the trousers leg is protected against scorching by pieces of pressing cloth, not shown, the said pieces of pressing cloth being stretched over the faces of the irons 9 and 10 and are being held in place by virtue of eyelets, the ends of the pieces of pressing cloth, which may be engaged over hooks on the casing sections 40 complementary to the irons. 90 95 100 105 110 115 120 125 130

In order to enhance the finished appearance of our novel apparatus, we would have it understood that in the discretion of a 130

manufacturer the casing sections 40 and any other appropriate portions of the apparatus may be nickel plated or may be otherwise embellished.

5 The construction herein illustrated and described constitutes the preferred embodiment of our invention and we have therefore described the same in detail with a view to imparting an exact understanding of both 10 structure and mode of operation. We do not desire, however, to be understood as confining ourselves to the specific construction and relative arrangement of parts as disclosed, our invention being defined by our appended 15 claims within the scope of which modifications in structure and relative arrangement of parts may be made without departure from our invention.

Having described our invention, what we 20 claim and desire to secure by Letters-Patent, is:—

1. An apparatus for pressing trousers while on the wearer, comprising a stand, an upright bracket connected to and carried by 25 the stand and arranged laterally thereto and having upper and lower apertured portions, irons having vertically disposed knuckles in vertical coincidence with the apertured portions of the bracket, an upright pindle extending through the apertured portions of 30 the bracket and the knuckles of the irons and arranged to open and close the irons tending through the apertured portions of

the bracket and the knuckles of the irons and hingedly connecting the irons together and to said bracket, means carried by the pindle and disposed above and below the irons for grasping trousers and holding the 35 same during a pressing operation, and means for pressing the irons together.

2. An apparatus for pressing trousers while on the wearer, comprising a stand, an upright bracket connected to and carried by 40 the stand and arranged laterally thereto and having upper and lower apertured portions, irons having vertically disposed knuckles in vertical coincidence with the apertured portions of the bracket, an upright pindle extending through the apertured portions of 45 the bracket and the knuckles of the irons and hingedly connecting the irons together and to said bracket, means carried by the pindle and disposed above and below the irons for 50 grasping trousers and holding the same during a pressing operation, and means for pressing the irons together; the said means being in the form of a clamp connected with 55 and arranged to open and close the irons and subject the same to pressure.

In testimony whereof we affix our signatures.

HERON B. LAMBERT.

JAY McCOMBS.
